COMBINED FILLING AND DISPENSING
VALVE FOR VOLATILE LIQUIDS

Louis B. Courtot, Cleveland, Ohio, assignor to The Weatherhead Company, Cleveland, Ohio, a corporation of Ohio

Application January 29, 1949, Serial No. 73,527

8 Claims. (Cl. 62—1)

1

This invention relates to filling and dispensing valves for tanks containing volatile liquids or gases liquefied under pressure, such as liquefied petroleum gas and the like. In certain installations as where liquefied petroleum gas is stored in dispensing tanks, it is necessary to provide means for each tank that will perform several functions, such as manually-controlled valve means to control dispensing the gas for consumption, means for filling the tank with the liquefied gas, means for testing the level of the tank to prevent overfilling, and means for relieving excess pressure from the tank.

It is an object of the present invention to perform such functions with a combination valve member having a single means for attachment to and communication with the tank without need for tubes extending into the tank (other than the gauge tube) or complex baffles in the valve body. This is accomplished by a novel and simple arrangement of ports, passageways, chambers, and the like, in a unitary valve body member, the result being that a single valve assembly may be employed to perform all the aforesaid functions, the device being very compact and economical to manufacture. The device may be fitted to the tank by means of a single fitting, preferably a single-threaded pipe nipple extending from the valve member, which greatly facilitates manufacture and installation.

Another object resides in providing for filling the tank with the volatile liquid or liquefied gas without interrupting the dispensing of the gas and without requiring other than the single tank attachment means referred to. This is accomplished, in a preferred embodiment of the invention, by forming a relatively large filling and dispensing bore concentric with the attachment nipple, the valve unit being mounted so that this bore is vertically disposed. A dispensing port intersects the bore near the upper end thereof for delivery of gas, this port being controlled by a manually operable valve. The filling port intersects the bore below the dispensing port and intersects the bore tangentially. During filling, the gas swirls around the lower periphery of the bore and enters the tank, leaving a central opening for the upward flow of gas to the dispensing port, there being no tendency for the gas to carry liquid out of the dispensing port.

It is a feature of the invention that a testing gauge tube may extend into the tank through the aforesaid vertical main bore whereby when the valve unit is mounted on the tank by means of the single fitting member, the gauge tube is

2

simultaneously fitted thereto. The aforesaid structure facilitates mounting the relief valve on the same unit, which may operate to close another passage intersecting the vertical or main bore above the entry point of the liquid thereto.

The manner in which the aforesaid objects and advantages are accomplished in the invention will be apparent from the following detailed description of a preferred embodiment thereto.

10 In the drawings:

Fig. 1 is a side elevation of the combination valve unit;

Fig. 2 is a plan view of the unit;

Fig. 3 is a partial section taken on 3—3 of Fig.

2;

Fig. 4 is a section taken on 4—4 of Fig. 1, the plane of section also being indicated on Fig. 3 for clarity;

Fig. 5 is a section of the complete valve unit taken on 5—5 of Fig. 4; and,

Fig. 6 is a partial section similar to Fig. 4 but taken through the center of the testing gauge as indicated on 6—6 of Fig. 3.

25 The valve unit comprises, in the preferred embodiment, an integral valve body which preferably is arranged so that it may be forged of brass, steel or any other suitable metal. As best seen in Figs. 1 and 3, the nipple N, preferably having pipe threads, forms the means for installing the combined valve unit on a tank. This nipple will be vertical, or substantially so, in actual operation. The other major components of the valve unit are; the dispensing nipple D

30 which is valved and controlled by the handle H, the filling nipple assembly F for charging the tank with volatile liquid or liquefied gas, the relief valve assembly R for relieving excess vapor pressure from the tank, and the test or fill gauge assembly G for indicating when the tank has

35 been filled to the desired level.

40 Describing the internal arrangements of the valve unit in more detail, within the nipple N is the bore 10, which is the main filling and dispensing bore. The upper portion of the bore 10 is intersected by the gas dispensing port 11 which is normally in communication with an outlet port 12 at right angles thereto which leads to the gas dispensing nipple D. Communication

45 between ports 11 and 12 may be cut off by the manually-controlled valve means, which includes movable valve member 13 carrying a soft seal for engaging the valve seat 14 surrounding the dispensing port 11. The valve member is opened and

50 closed by manipulation of a handle H, and

although the details of the valve-operating structure are not part of the invention, I prefer to provide a compact packless valve such as that described in the co-pending application of Louis B. Courtot, Serial No. 64,573, filed December 10, 1948.

Relief valve assembly R is included in the form by providing a relief bore 15 that intersects the vertical bore 10. It includes movable valve member 16, spring 17 for closing the valve, and a retaining nut 18 for retaining the spring. The details of this assembly form no part of the invention and suitable assemblies for the combination are completely described in the application of Andrew G. Johnson, Serial No. 785,939, filed November 14, 1947 and Theodore A. St. Clair, Serial No. 58,563, filed November 5, 1948, now Patent No. 2,527,381, either of which is suitable for use with the valve unit of this invention.

Filling assembly F is mounted in a laterally offset enlargement 20 of the valve body. It includes a bore 21 parallel to main bore 10 and which houses a reciprocably-mounted valve member 22 urged outwardly by a spring 23. The valve member carries a soft seat 26 for sealing the filling port. Valve seat member 27 is threaded in the enlargement 20 by means of threads 28, the lower portion of the member having a hard seat 29 for engaging the soft seat 26 in the movable valve element. Member 27 may have a tapered bore 30 for sealing engagement with a filling nipple, which also may engage a projection in the form of a screw 31 on the movable valve member 22 for opening the valve member to permit the inlet of the liquid. The outer portion of the enlargement 20 is threaded as at 33 to receive a closure and sealing cap member 34. Leading from a lower portion of bore 21 is a passageway 35 which intersects the bore 10 as at 35a well below the dispensing ports 11 and 12. As seen in Fig. 5, passageway 35 is disposed tangentially relative to vertical bore 10, the result being that liquid entering the bore 10 during the filling operation is given a circumferential or tangential motion causing it to swirl around in the bore and leaving a more or less well-defined central passageway for the flow of gas upwardly and out of the dispensing port. Thus, service or dispensing of gas may be continued during the filling operation without the need for interrupting either operation.

It is customary to provide means to indicate the liquid level within the tank so that the filling of the tank may be interrupted in time to leave a vapor space above the liquid level. This may be provided in the invention without materially complicating the structure of the valve unit by incorporating test structure G including a gauge tube 36 that is disposed in the vertical bore 10 and threaded into the valve body above the upper end of the bore at 37. A valve seat 38 is formed about a passageway in communication with the tube 36 and the passageway may be closed by a manually-operable plug member 39 threaded in the body and carrying a soft seal 41. As seen in Fig. 3, a small bleed passageway 42 leads from an area outside of the valve seat 38 to the surface of the valve. The length of tube 36 below the top of the tank represents the desired vapor space, and during the filling operation plug 39 is unscrewed so that the bleed passage 42 is open to the interior of the tank. When the liquid level reaches the bottom of the tube 36, the vapor pressure thereupon forces liquid up into the tube and a small amount of liquid is vis-

ible at the opening 42 signaling the operator to cease filling the tank.

It can be seen that all the various functions necessary for this service can be carried out by a single valve member having a single attaching nipple, made of a minimum of material, and having minimum over all dimensions. Installation is thereby greatly simplified and the manufacture is very economical because of the saving in material made possible by the novel arrangement of elements exemplified by the illustrated embodiment of the invention. The valve body can be readily designed for production by forging or by casting operations despite the relatively great number of functions performed by the unit.

Although I have described a preferred embodiment of my invention, it will be understood that the appended claims and not the aforesaid embodiment is determinative of the scope of my invention.

What is claimed is:

1. A filling and dispensing valve for volatile liquids comprising a valve body having a bore and means for mounting said valve on a tank with said bore generally vertically disposed, a liquid filling connection formed in said body to one side of and adjacent the upper end of said bore, a straight filling passageway leading downwardly from said filling connection and intersecting said bore adjacent the lower end thereof, the outer wall of said filling passageway being disposed tangentially to the wall of said bore at the intersection therewith, the axis of said passageway forming an acute angle with the axis of said bore, a gas dispensing outlet intersecting said bore above the intersection of said filling passageway and said bore, and a valve for closing said gas dispensing outlet.

2. A filling and dispensing valve for volatile liquids comprising a valve body having a bore and means for mounting said valve on a tank with said bore generally vertically disposed, a liquid filling connection formed in said body, a filling passageway leading downwardly from said filling connection and intersecting said bore tangentially, a gas dispensing outlet intersecting said bore above the intersection of said filling passageway and said bore, a valve for closing said gas dispensing outlet, a fill gauge tube extending within said bore and fastened in the upper end wall thereof, and a valved testing outlet in said body for said gauge tube.

3. A filling and dispensing valve for volatile liquids comprising a valve body having a bore and a nipple surrounding the same for mounting said valve on a tank with said bore generally vertically disposed, a liquid filling connection formed in said body, a filling passageway leading downwardly from said filling connection and intersecting said bore tangentially, a gas dispensing outlet intersecting said bore above the intersection of said filling passageway and said bore, a valve for closing said gas dispensing outlet, a fill gauge tube extending within said bore and fastened in the upper end wall thereof, and a valved testing outlet in said body for said gauge tube.

4. A filling and dispensing valve for volatile liquids comprising a valve body having a bore and a nipple surrounding the same for mounting said valve on a tank with said bore generally vertically disposed, said body including a laterally offset body portion parallel to said bore, a liquid filling connection formed in said body off-

set portion to one side of and adjacent the upper end of said bore, a straight filling passageway leading downwardly and angularly from said filling connection and intersecting said bore adjacent the lower end thereof, the outer wall of said filling passageway being disposed tangentially to the wall of said bore at the intersection therewith, the axis of said passageway forming an acute angle with the axis of said bore, a gas dispensing outlet intersecting said bore above the intersection of said filling passageway and said bore, and a valve for closing said gas dispensing outlet.

5. A filling and dispensing valve for volatile liquids comprising a valve body having a bore and means for mounting said valve on a tank with said bore generally vertically disposed, a liquid filling connection formed in said body, a filling passageway leading downwardly from said filling connection and intersecting said bore tangentially, a gas dispensing port intersecting said bore above the intersection of said filling passageway and said bore, a generally radially extending extension aligned with said port, a valve in said extension for closing said dispensing outlet, a dispensing nipple extending generally perpendicular to said bore and to said extension, and passageway means establishing communication between said dispensing nipple and port when said valve is open.

6. A filling and dispensing valve for volatile liquids comprising a valve body having a bore and means for mounting said valve on a tank with said bore generally vertically disposed, said body including a laterally offset body portion parallel to said bore, a liquid filling connection formed in said offset body portion, a filling passageway leading downwardly and angularly from said filling connection and intersecting said bore tangentially, a gas dispensing port intersecting said bore above the intersection of said filling passageway and said bore, a generally radially extending extension aligned with said port, a valve in said extension for closing said dispensing outlet, a dispensing nipple extending generally perpendicular to said bore and to said extension, and passageway means establishing communication between said dispensing nipple and port when said valve is open.

7. A filling and dispensing valve for volatile liquids comprising a valve body having a bore and means for mounting said valve on a tank

with said bore generally vertically disposed, a liquid filling connection formed in said body, a filling passageway leading downwardly from said filling connection and intersecting said bore tangentially, a gas dispensing port intersecting said bore above the intersection of said filling passageway and said bore, a generally radially extending extension aligned with said port, a valve in said extension for closing said dispensing outlet, a dispensing nipple extending generally perpendicular to said bore and to said extension, passageway means establishing communication between said dispensing nipple and port when said valve is open, a fill gauge tube extending within said bore and fastened in the upper end wall thereof, and a valved testing outlet in said body for said gauge tube.

8. A filling and dispensing valve for volatile liquids comprising a valve body having a bore and means for mounting said valve on a tank with said bore generally vertically disposed, said body including a laterally offset body portion parallel to said bore, a liquid filling connection formed in said offset body portion, a filling passageway leading downwardly and angularly from said filling connection and intersecting said bore tangentially, a gas dispensing port intersecting said bore above the intersection of said filling passageway and said bore, a generally radially extending extension aligned with said port, a valve in said extension for closing said dispensing outlet, a dispensing nipple extending generally perpendicular to said bore and to said extension, passageway means establishing communication between said dispensing nipple and port when said valve is open, a fill gauge tube extending within said bore and fastened in the upper end wall thereof, and a valved testing outlet in said body for said gauge tube.
